(57) **CLAIM**

We claim the ornamental design for a portable access device, as shown and described.

DESCRIPTION

FIG. 1 is a front perspective view of our design for a portable access device in an open configuration.

FIG. 2 is a front elevation thereof.

FIG. 3 is a rear elevation thereof.

FIG. 4 is a right side view thereof.

FIG. 5 is a left side view thereof.

FIG. 6 is a bottom view thereof.

FIG. 7 is a top view thereof.

FIG. 8 is a front perspective view thereof, in a closed configuration.

FIG. 9 is a front perspective view of another embodiment of our design for a portable access device.

FIG. 10 is a front elevation thereof.

FIG. 11 is a rear elevation thereof.

FIG. 12 is a right side view thereof.

FIG. 13 is a left side view thereof.

FIG. 14 is a bottom view thereof; and,

FIG. 15 is a top view thereof.
